UNITED STATES PATENT OFFICE

SIGURD RUMP, OF ZURICH, SWITZERLAND, ASSIGNOR TO AKTIENGESELLSCHAFT BROWN, BOVERI & CIE., OF BADEN, SWITZERLAND, A JOINT-STOCK COMPANY OF SWITZERLAND

FLUID FILLED SWITCH

Application filed August 27, 1930, Serial No. 478,044, and in Germany September 2, 1929.

This invention relates to improvements in electric switches and particularly to switches in which the circuit is broken in a conductive fluid such as water.

5 When a circuit is broken by a switch of the above character, an arc is formed between the switch contacts. The current density in such arc is very high and attempts have been made to decrease the current density thereof 10 by increasing the area of the contact surfaces between which the arc is formed. Such enlarged contacts, however, require a much greater expenditure of energy to secure proper acceleration in separation of the contacting surfaces due to the greater masses 15 to be moved which causes constructions materially enlarging the size of the switch and increasing the cost thereof.

It is, therefore, among the objects of the 20 present invention to provide an electric switch making and breaking an electric circuit in a conductive fluid in which the arc formed is so distributed as to decrease the current density therein.

25 Another object of the invention is to provide an electric switch operating in a conductive fluid in which the surfaces in contact with the arc are enlarged without enlarging the size of the movable contact of the switch.

30 Another object of the invention is to provide an electric switch operating in a conductive fluid in which a plurality of metallic surfaces are arranged in the path of the arc in such a manner that the movable contact 35 remains in contact with such metallic surfaces throughout the entire movement of such contact.

Objects and advantages, other than those 40 above set forth, will be apparent from the following description when read in connection with the accompanying drawing in which:

45 Fig. 1 is a somewhat schematic elevational view illustrating a switch embodying my invention; and

Fig. 2 is a plan view showing the relation of the movable contact element to current distributing plates illustrated in Fig. 1.

50 Referring more particularly to the drawing by characters of reference, the reference

numeral 1 designates a plate with which the engaging clips 2 forms both one pole of the switch structure and a bottom plate of a tank completed by a substantially cylindrical wall 3 of insulating material, which tank is filled with and retains a body 4 of conductive fluid such as water. A movable contact 6 in the form of a rod or other suitable light shape extends into the tank and is arranged to be moved into or out of engagement with the fixed contact 2 by suitable means (not shown).

A plurality of metallic plates 7 are arranged over each other in spaced relation and are thus supported by suitable fastenings 65 with the insulating wall 3. The plates are formed with central apertures along the line of movement of movable contact 6. Spring contacts 8 are fastened to the plates 7 and extend into sliding engagement with movable contact 6 throughout substantially its entire path of movement. When movable contact 6 is raised out of engagement with the fixed contact 2, the current between the contacts is spread out either between the fixed contact and a plate or between several plates thereby materially decreasing the density of the current and preventing the formation of an arc.

It will thus be seen that the present invention provides an electric switch in which the circuit is broken within a body of conductive material provided with means whereby the current is so distributed as to be at low density thereby preventing arc formation. The size of the contacts remains the same as heretofore or may even be decreased and the operating means (not shown) need not be enlarged over those used previously. The 80 switch is, therefore, quick-acting, can be used for high currents and is cheap to construct.

Although but one embodiment of the present invention has been illustrated and described, it will be apparent to those skilled in the art that various changes and modifications may be made therein without departing from the spirit of the invention or from the scope of the appended claims.

The invention claimed is:

1. In an electric switch, a tank having an

electrically conductive fluid contained therein, a fixed contact disposed within said tank in contact with the said fluid, a plurality of electrically conductive members arranged 5 within said tank in contact with said fluid, the said members being insulatingly disposed one from each other and from the tank, and a movable contact member disposed for movement into connection with and disconnection 10 from said fixed contact and said members, the arrangement of said fixed contact and members being such that the said movements of the movable contact effects the sequential disconnection thereof from the said fixed contact 15 and members to inhibit the establishment of arcs at times of such movements.

2. In an electric switch comprising a receptacle containing an electrically conductive fluid, a fixed contact supported within said 20 receptacle in contact with said fluid, a plurality of spaced plates of electrically conductive material fixedly supported within said receptacle in contact with said fluid and each having an aperture therein, contact members 25 severally arranged about said apertures in electrically conductive connection with said plates, and a cooperating contact arranged for movement within said fluid through said apertures sequentially into and out of connection with said members and said fixed contact, the said plates and fluid being operable 30 to inhibit the establishment of arcs during movements of said cooperating contact.

3. In an electric switch comprising a receptacle containing an electrically conductive fluid, a fixed contact supported within said receptacle in contact with said fluid, a plurality of spaced electrically conductive members fixedly supported within said receptacle 40 in contact with said fluid, contact members severally arranged in electrical connection with said members, and a cooperating contact arranged for movement sequentially into and out of electrical connection with said contact 45 members and said fixed contact, the said spaced members and fluid constituting a path for the flow of electric current between said contacts and being operable to vary the flow of current between said fixed contact and said 50 cooperating contact during said movements of the latter.

4. In combination with switching means for controlling electric circuits comprising a fixed contact and a cooperating movable contact, of a receptacle containing an electrically conductive fluid, a plurality of spaced electrically conductive members fixedly supported within said receptacle in contact with said fluid, and contact members severally arranged 55 in electrically conductive connection with said members, the said cooperating contact being arranged for movement sequentially into and out of connection with said contact members and said fixed contact, and the said members 60 and fluid constituting a path for the flow of

current between said contacts and being operable to vary the flow of current between said fixed and cooperating contact during said movements of the latter.

In testimony whereof I have hereunto subscribed my name this 16th day of August, A. D. 1930.
